LADY'S ROBE

Sadie Shaw, New York, N.Y., assignor to B. Cohen & Co.,
Inc., New York, N.Y., a corporation of New York

Application June 10, 1959, Serial No. 56,289

Term of patent 3½ years

(Cl. D3—26)

Fig. 1 is a front perspective view of a lady's robe, showing my new design;

Fig. 2 is a front elevational view of the patch pocket on the robe of Fig. 1; and

Fig. 3 is a top view of said pocket.

The back of the robe is conventional.

The dominant feature of my invention resides in the portions shown in full lines, the same constituting the patch pocket.

I claim:

The ornamental design for a lady's robe, substantially as shown and described.
